FIG. 1 is a perspective view of a plant container stabilizer of
the present invention;

FIG. 2 is a top plan view thereof;

FIG. 3 is a right side view thereof, the left side being a mirror
image;

FIG. 4 is a front view thereof;

FIG. 5 is a bottom plan view thereof; and,

FIG. 6 is a rear view thereof.

The broken lines depict portions of the plant container stabi-
lizer that form no part of the claimed design.
